Oil Development Company, a corporation of
Delaware

Application August 4, 1944, Serial No. 548,018

3 Claims. (Cl. 260—677)

The present invention is directed to a method for recovering relatively pure normal butylenes from a hydrocarbon C₄ fraction composed of a mixture of butanes and iso- and normal butylenes, such as that obtained from a cracking operation.

Normal butylenes have become increasingly important with the need for greater quantities of butadiene for the production of synthetic rubber. One of the most feasible methods for producing butadiene is to dehydrogenate normal butylenes. In order to obtain satisfactory yields and conversions per pass in this process, it is important that the normal butylenes be in a relatively pure state because other C₄ hydrocarbons react at a very low rate and consequently tend to build up to an intolerable concentration in the dehydrogenation circuit, causing loss in capacity or additional purification facilities. It is particularly important that the normal butylene subjected to dehydrogenation for production of butadiene be free from isobutylene and iso- and normal butanes not only because the presence of these hydrocarbons in this reaction introduce difficulties for the reasons mentioned, but because the isobutylene and isobutane are in themselves extremely valuable starting materials for the production of many vital products and must be conserved whenever possible.

The conventional method for recovering normal butylene from a mixture thereof with butanes and isobutylene is to subject the mixture to a cold acid extraction process, by which is meant the contacting of the hydrocarbon mixture with about 65% sulfuric acid at a temperature between about 60° and 90° F. Sulfuric acid of this strength at these temperatures has a selective absorption action for isobutylene. The result is that isobutylene of about 97% purity is recovered from the acid extract, leaving a residual gas containing butanes and normal butylene. This gas mixture is then extracted with acetone or a similar solvent having selective solvent power for olefins as compared to paraffins. From this extraction step there is recovered a C₄ hydrocarbon mixture containing about 90% of normal butylene. In general, it may be stated that slightly less than half of the normal butylenes contained in the feed stock to this conventional method is recovered, and then only in admixture with 10% of other C₄ hydrocarbons.

According to the present invention the yield and purity of normal butylenes recovered from mixtures thereof with C₄ hydrocarbons may be

increased by following a different sequence of steps, including, first, a hot acid copolymerization of the iso- and normal butylenes contained in the C₄ mixture, followed by catalytic cracking of the resulting copolymer and then by cold acid absorption of isobutylene from the normal butylenes. By this procedure the yield of normal butylenes may be increased to better than 90% and the purity to a value in the neighborhood of 97%.

The nature of the present invention may be more clearly understood from the following detailed description of the accompanying drawing, in which the single figure is a flow plan showing the nature and order of the processing steps to which a C₄ hydrocarbon mixture is subjected according to the present invention.

Referring to the drawing in detail, numeral 1 designates a hot acid copolymerization unit. As is known, this operation is carried out by contacting a mixture of iso- and normal butylene in the presence of 60% to 70% sulfuric acid at a temperature between about 140° and 160° F. To this unit is fed a C₄ hydrocarbon mixture containing normal and isobutylenes and normal and isobutanes. This mixture may be obtained from several refinery operations, such as catalytic and thermal cracking, thermal polymerization and the like. Generally, the process of the present invention is applied more advantageously, relative to the conventional procedure, to a C₄ cut obtained from a thermal cracking unit, because in this cut the content of normal butylenes is considerably lower than in the C₄ cut obtained from catalytic cracking. This C₄ cut is fed to unit 1 by way of line 2.

The acid is separated from the hydrocarbon phase in the copolymerization unit by settling, the hydrocarbon phase is drawn off, and the bulk of the unreacted saturates is removed by distillation, while the heavy fraction containing the copolymer resulting from the distillation operation is subjected to hydrolysis with dilute caustic for the decomposition of any esters present. The hydrolyzed copolymer fraction is then subjected to a second distillation operation for the production of a substantially pure copolymer fraction. These distillation and neutralization operations are embodied in block 1 of the flow plan, from which the copolymer fraction, substantially free from iso- and normal butanes which are withdrawn from the unit by way of line 3, is fed by line 4 to a catalytic cracking unit 5. This unit also embodies fractionation steps for the separation of the fractions into the desired products.

The catalytic cracking is advantageously carried out by passing the copolymer through a catalyst bed comprised of attapulgus clay or natural clay which has been acid washed, such as "Super Filtrol," at from 600° to 900° F. and under 1 to 5 atmospheres pressure, while utilizing a feed rate or a residence time of the feed stock in the reactor such that 30% to 45% of the total feed is converted per pass into a mixture which is primarily iso- and normal butylene in approximately equal amounts, but also containing small quantities of hydrocarbons lighter and heavier than C₄ hydrocarbons. The effluent from the catalytic reactor is fractionated, the unconverted copolymer recycled to the reactor and the C₄ fraction, containing iso- and normal butylenes, withdrawn by way of line 6. The lighter constituents are withdrawn from the catalytic cracking unit through line 7 and the residues by way of line 8.

The iso- and normal butylenes in line 6 are then fed to a cold acid process unit 9 of the type heretofore described. It may be observed that this unit includes not only an extraction stage in which the sulfuric acid extracts the isobutylene from the C₄ mixture, but a desorption stage in which the extracted isobutylene are liberated from the sulfuric acid. This liberated isobutylene leaves the unit by way of line 10. A portion of this isobutylene, to the extent that it is required to adjust the content of isobutylene in the feed stock to the hot acid process so that this stock will contain equal molecular proportions of isobutylene and normal butylenes is recycled to hot acid copolymerization unit. It may be observed here that in the event the feed stock is one which contains more isobutylene than normal butylenes, the molecular proportions of these constituents are adjusted by the addition of normal butylenes. The remainder of the isobutylene is withdrawn from the system.

The normal butylenes leaving the cold acid processing unit 9 through line 11 will be about 97% pure. This substantially pure material is fed to a dehydrogenation unit 12 for the catalytic dehydrogenation of normal butylenes to butadiene. From this point on, the process is the same as that previously practiced, the effluent from the dehydrogenation unit passing by way of line 13 to an extraction system.

If it be assumed that the feed to the hot acid process is composed of 17.3% isobutane, 51.2% normal butane, 8.2% isobutylene and 23.3% normal butylenes, the composition of this feed is adjusted according to the present invention by adding sufficient isobutylene to yield a resulting composition having 15% isobutane, 44.6% normal butane, 20.2% isobutylene and 20.2% normal butylenes. On the basis of a feed of 100 barrels, this would mean an addition of 15.1 barrels of recycled isobutylene by way of line 10 containing 97% isobutylene and 3% of normal butylene, making a total feed to the hot acid process of 115.1 barrels, which may be expected to yield copolymer equivalent to 46 barrels of iso- and normal butylenes. Operated under the conditions outlined above, the catalytic cracking operation will ordinarily yield from 46 equivalent barrels of copolymer feed about 42.3 barrels of product, leaving the unit through line 6, of which about 98% constitutes isobutylene

and normal butylenes in equal amounts. Thus, this product will contain about 20.75 barrels of each of these butylenes. From this quantity of feed of this composition to the cold acid process 5 there may be expected a recovery of 20.2 barrels of a normal butylene cut containing 97% normal butylenes, 1% isobutylene and 2% butanes. In contrast to this result, a hundred barrels of the same C₄ cut processed according to the method 10 formerly practiced yielded about 11.3 barrels of normal butylene fraction containing about 90% of normal butylenes. Thus, the process of the present invention represents a considerable improvement in the recovery of normal butylenes 15 from refinery C₄ cuts containing them in admixture with isobutylene and butanes.

It will be apparent that the process of the present invention is susceptible to considerable variation without any departure from its essential nature. For example, the copolymerization step 20 may be conducted with different catalysts and under different conditions, most of which are known. Likewise, the cold acid extraction of isobutylene may be replaced by any other suitable 25 operation for the quantitative separation of normal butylenes from isobutylene. The particular processing steps described are given for illustrative purposes merely because they represent the most conventional operations for the purposes intended and the ones most likely to be employed 30 in the commercial practice of the process of the present invention.

The nature and objects of the present invention having been fully described and illustrated, what 35 I wish to claim as new and useful and to secure by Letters Patent is:

1. In a method for recovering normal butylenes from a C₄ fraction containing them in admixture with isobutylene and butanes, the steps which 40 comprise adjusting the composition of said C₄ fraction to the extent necessary to provide in it equal molecular proportions of isobutylene and normal butylenes, subjecting the resulting mixture to a treatment suitable for the copolymerization 45 of normal and isobutylenes, separating the resulting copolymer from the product of this treatment, subjecting said copolymer to catalytic cracking under conditions suitable for the cracking of the copolymer into its component parts with a minimum 50 production of gas and coke, recovering a mixture of normal and isobutylenes from said cracking operation, and recovering substantially pure normal butylenes from said mixture.
2. A method according to claim 1 in which the 55 mixture of normal and isobutylenes from the cracking operation is subjected to extraction with sulfuric acid under conditions suitable for the preferential absorption of normal butylenes and substantially pure normal butylenes are recovered 60 from the sulfuric acid.
3. A method according to claim 1 in which the original C₄ fraction contains butylene in excess of isobutylene, the mixture of normal and isobutylenes from the cracking operation is separated into 65 its components and at least a part of the isobutylene is recycled to the feed to the copolymerization operation in order to adjust the ratio of isobutylene to normal butylenes in said feed.
